US0D1029629S

(12) **United States Design Patent** (10) **Patent No.:** **US D1,029,629 S**
(45) **Date of Patent:** **** Jun. 4, 2024**

(54) **CARTON**

(71) Applicant: **Graphic Packaging International, LLC**, Atlanta, GA (US)

(72) Inventor: **Greg Gunner**, Cobourg (CA)

(73) Assignee: **Graphic Packaging International, LLC**, Atlanta, GA (US)

(**) Term: **15 Years**

(21) Appl. No.: **29/840,644**

(22) Filed: **May 31, 2022**

(51) LOC (14) Cl. **09-03**

(52) U.S. Cl.

USPC **D9/414; D9/420**

(58) **Field of Classification Search**

USPC D9/414, 415, 416, 417, 418, 419, 420,

(57) **CLAIM**

The ornamental design for a carton, as shown and described.

DESCRIPTION

FIG. 1 is a perspective view of a carton showing my new design.

FIG. 2 is a left elevation view of the carton of FIG. 1, the right elevation view is a mirror image.

FIG. 3 is a front elevation view of the carton of FIG. 1.

FIG. 4 is a rear elevation view of the carton of FIG. 1.

FIG. 5 is a top plan view of the carton of FIG. 1.

FIG. 6 is a bottom plan view of the carton of FIG. 1.

FIG. 7 is a perspective view of the carton of FIG. 1 shown in an open configuration.

FIG. 8 is another perspective view of the carton of FIG. 1 shown in an open configuration; and,

FIG. 9 is a plan view of the carton of FIG. 1 shown in an unfolded configuration.

1 Claim, 9 Drawing Sheets
